UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,153,499.

Specification of Letters Patent.

Patented Sept. 14, 1915.

Application filed February 21, 1914. Serial No. 820,194.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

My invention relates to typographical machines, such as linotype machines of the general organization represented in U. S. Letters Patent, No. 436,532, to O. Mergenthaler, wherein circulating matrices are released 10 from a magazine in the order in which their characters are to appear in print and then assembled in line, the composed line transferred to the face of a mold, the mold filled with molten metal to form a slug or 15 linotype against the matrices which produce the type characters thereon, and the matrices thereafter returned through distributing mechanism to the magazine from which they started. More specifically, it relates to machines of this kind, when equipped with 20 means for reversing the matrices during assemblage, and for again reversing them when necessary prior to distribution, as shown for instance in U. S. Letters Patent 25 to Holbourns and Longhurst, No. 951,948, wherein the matrices thus dealt with are formed with intaglio characters in their opposite edges, or such as are known in the art as Janus-faced matrices.

In the accompanying drawings, I have shown my improvements in preferred form and by way of example, and as applied to the style of machine mentioned, but obviously many changes and variations may 35 be made therein, and in their mode of application, which will still be comprised within the spirit of the invention. Thus, they may be adapted to other forms of typographical machines, such as typesetters, typecasters, and 40 the like, which handle type or dies, instead of matrices. Generally speaking, I desire it to be understood that I do not limit myself to any specific form or embodiment, except 45 in so far as such limitations are specified in the claims.

Referring to the drawings: Figure 1 is a front elevation of a portion of a linotype machine with my improvements embodied therein; Fig. 2 is a partial rear elevation of 50 the separating and distributing mechanism;

Fig. 3 is a front elevation of the assembling and reversing means; Fig. 4 is a perspective view of the reversing devices; Fig. 5 is a perspective of certain of the separating and distributing elements; Fig. 6 is a section 60 through the separating devices on the line 6-6 of Figs. 9 and 10; Figs. 7 and 8 are similar views showing the parts in operative condition; Fig. 9 is a section on the line 9-9 of Fig. 6; Fig. 10 is a similar view 65 showing the parts in different relations; Fig. 11 is a detail of a modification; Figs. 12 and 13 are details of the separating means, showing the parts in different relations; Fig. 14 is an inside perspective detail thereof; Fig. 15 illustrates a matrix, and Fig. 16 a modified form thereof; and Fig. 17 is an edge 70 view of two matrices.

As is usual in machines of this kind, the matrices are stored in the magazine A and 75 are released therefrom by the manipulation of the keys A¹, when they pass to the assembler A². The composed line is then transferred to other mechanism wherein it is justified and the slug is cast and trimmed, 80 after which the matrices are moved onto the second elevator A³, and are raised to the upper part of the machine and then shifted into the distributor box A⁴, from which they are individually delivered to the further distributing mechanism by the lifting device or finger A⁵. Except in so far as hereinafter mentioned, these parts are or may be of any usual or well known construction, which in 85 itself constitutes no part of my invention. 90 As shown in Fig. 15, the matrices X are formed with intaglio characters in both of their edges, and in order that either of these characters may be brought into operation at will, I have provided reversing devices 95 somewhat similar to those disclosed in the Holbourns and Longhurst patent. These devices comprise (Figs. 1, 3 and 4) the adjustable chute B interposed between the magazine and assembler, the chute being 100 formed with two channels, one C straight or plain and through which the matrices pass in the normal manner, and the other D rifled or tortuous so that the matrices are reversed in their passage. The chute B is 105 preferably mounted upon the slide B¹ suitably guided on the main frame and provided with the spring B², connected at its upper end to a pin fixed to the framework of the machine and tending normally to 110

hold the chute in its uppermost position and with the straight passage C in operation. By means of the key E the chute may be depressed so as to bring the reversing or rifled throat D into operation, and to this end the key is provided with the suitably formed link or connection E¹ carrying the roller E², to engage the outer end of the pivoted arm E³. The arm E³ passes across the face of the slide B¹ in position to engage a projecting stud thereon, the parts being so arranged that when the key E is depressed, the arm is swung about its pivot and the slide is moved to bring the rifled passage D into operative position, as shown in Fig. 4. At this time the key E may be engaged with the notch E¹⁰ in the framework, so that the several devices will be held against movement. When the key is freed from the notch, the spring B¹ is permitted to act and the slide is elevated to bring the plain passage C into operative position, as shown in Fig. 3, the force of the spring being sufficient also to restore the key and the other connected parts to normal position, although additional springs may be employed for this purpose, if desired. After the casting operation, and the lifting of the matrices by the second elevator A³, they are introduced into the distributor box A⁴, the advance of the line being checked by the contact of the matrix ears X² with the rail abutments F (see Figs. 5, 9, 12, 13 and 14), after which they are elevated one by one by the finger A⁵. The means for securing the individual disengagement of the matrices at this point are substantially similar to those disclosed in the application for Letters Patent of John R. Rogers, filed November 26, 1912, Serial No. 733,586, it being noted that both the abutments F and the overlying blades F¹ engage only with the ears X² of the matrices, and that the horizontal distance between the abutments and blades is sufficient only to permit the upward passage of a single matrix at a time. In the said Rogers application these elements were primarily illustrated in connection with a line of matrices having their guiding ears all located at their rear sides in the line of travel, but in the present instance they are employed in connection with mixed lines comprising both reversed and unreversed matrices, and accordingly wherein frequently the ears of two consecutive matrices will be in immediate contact. Therefore in order to prevent the possibility of two matrices being simultaneously disengaged in such circumstances, I construct the ears of such size that the aggregate thickness of two of them is greater than the horizontal distance between the abutments F and blades F¹. Fig. 17 illustrates two matrices, one thick and the other thin, and with their ears X² of different thickness. However, the thickness of the

smallest ears is always greater than half that of the largest ears, so that even when two are brought together there will be insufficient space between the abutments F and blades F¹ to permit the passage of the 70 second matrix. Thus, in Fig. 12 two thin-eared matrices, one reversed and the other unreversed are shown in contact, but with the ears of the second matrix engaged by the blades F¹ and consequently held against 75 elevation; and in Fig. 13 is illustrated the detachment of a single thick-eared matrix.

As the matrices are separated individually they are delivered to the grooved bar G, along which they are caused to travel by 80 the screws G¹, all in the usual manner. The construction of the bar and of the devices coöperating therewith is such as to effect the separation of the reversed matrices from those unreversed, after which further means 85 are employed to effect the reversal of the former, so that all will be restored to the magazine in their original position. The bar G (Figs. 5, 9 and 10) is formed with two toothed portions separated by the plain 90 or untoothed portion G², substantially in the manner presented in U. S. Letters Patent to J. R. Rogers, No. 890,303. Immediately beneath the untoothed portion G² is located the bridge H (Figs. 6, 7 and 8), and the matrix X (Fig. 15) is formed in its bottom edge at one side with the notch X¹. The relation of the bridge and notch is such that they will register when the matrix is in normal position, and will be out of registry when the 100 matrix is reversed. In Fig. 16, a modified matrix Y is illustrated, wherein a single extended notch Y¹ is formed, which is adapted because of its size to perform the function of the previously mentioned notch X¹ as well 105 as that of the ordinary central notch X¹⁰, shown in Fig. 15. As the matrices X pass along the bar G, they become disengaged therefrom at the untoothed portion G². At this point the unreversed matrices (Fig. 7) 110 drop from the bar because of the registry of the notches X¹ with the bridge H; whereas the reversed matrices (Fig. 8) are sustained by the bridge until they are brought into engagement with the further toothed portion of the bar G, in substantially the manner described in the said Rogers patent. When the unreversed matrices pass from the bar, (Figs. 9 and 10) their ears X² fall upon 115 and are supported by the projecting pieces J, located in proper position to receive and temporarily sustain them. Similarly the reversed matrices pass along the second toothed portion of the bar, and as they fall from the end thereof, their ears X² drop onto and are temporarily sustained by the projecting pieces K. Immediately beneath the end of the projections J is located the mouth of the straight tube L (see also Figs. 2 and 5), and beneath the end of the pieces 120 125 130

K is the mouth of the rifled or reversing tube M. As the matrices on the projections J and pieces K are still engaged by the threads of the screws G¹, they are shifted laterally until they clear their respective supports, when the unreversed matrices pass through the plain tube L, and the reversed matrices through the rifled tube M which acts to re-reverse them during their passage.

10 The lower ends of the tubes L and M converge, and the matrices passing therethrough, all of them in their original and normal position, are thus delivered to the regular distributor box N, and from it by 70

15 the lifting finger N¹ to the ordinary distributing mechanism N², whereby they are restored to their proper channels in the magazine in the manner well understood in the art.

20 In order to prevent the simultaneous passage of matrices from both the tubes L and M, and their consequent improper delivery to the distributor box N, I have adopted a special arrangement of the supporting members 75

25 J and K with relation to the screws G¹. As shown in Figs. 9 and 10, the ears X² of the unreversed matrices are foremost while the ears of the reversed matrices are rearmost, in their line of travel; and similarly 80

30 the distributing teeth X³ of the unreversed matrices are rearmost and of the reversed matrices foremost. Therefore (Fig. 10), it will be seen that the ears of the reversed matrices will not be freed from the supports 85

35 K until the matrices have passed entirely beyond them; while the unreversed matrices (other conditions being the same) will drop from the projections J at a relatively earlier period, namely, as soon as the forward ears 90

40 X² pass thereover. Making due allowance for these different points of disengagement, I so proportion the supports J and K with 95

45 relation to each other, and with reference to the pitch of the threads on the screw G¹, as to prevent the simultaneous or approximately simultaneous disengagement of matrices from the respective supports; and preferably I arrange the parts so that the matrices will be released from the supports J 100

50 and K respectively at intervals of 180° in the rotation of the screws.

Fig. 11 illustrates a modified form, wherein the supporting blocks K are omitted, and the reversed matrices are dropped directly 105

55 from the bar G into the rifled tube. In this instance the necessary periodicity is secured by the employment of matrices formed with the distributing teeth X⁴, which extend entirely through the body of the matrix, instead of being located in a flange more or less to one side thereof, as is shown in Figs. 9 and 10. In this modified form, the unreversed matrices drop from the projections J 110

60 into the tube L in the same manner as previously described, whereas the reversed mat-

rices are caused to travel a farther distance than in the previous instance, and to pass to the extreme end of the bar G before being disengaged therefrom, and then drop directly therefrom into the tube M, the several 70 parts being suitably proportioned to obtain the proper interval of delivery.

As previously stated, I have shown my improvements in preferred form and by way of example, and as applied to a specific 75 style of machine, but obviously many modifications and alterations therein, and in their mode of adaptation, will suggest themselves to those skilled in the art, without departure from the scope of the invention.

Having thus described my invention, its construction and mode of operation, what I claim and desire to secure by Letters Patent of the United States, is as follows:

1. In a typographical composing machine, 85 assembling mechanism comprising, in combination, reversing means for the type or matrices movable into and out of operative position, devices for holding said means in one of their positions, and automatic means 90 for returning them to their other position when released by said devices.

2. In a typographical composing machine, assembling mechanism comprising, in combination, the reversing chute B for the type 95 or matrices, the operating arm E³, the finger key E, and the connected link E¹ provided with the roller E² to engage the chute operating arm.

3. In a typographical machine, the combination of a composed line containing reversed and unreversed type or matrices, means for detaching the type or matrices individually from the line, two distributor tubes, one plain and the other rifled, and 105 automatic mechanism independent of the detaching means to receive the detached type or matrices and deliver them into one or the other of the tubes according to whether they are reversed or unreversed.

4. In a typographical machine, the combination of a composed line containing reversed and unreversed type or matrices, means for detaching the type or matrices individually from the line, two distributor tubes, one plain and the other rifled, and automatic mechanism independent of the detaching means to receive the detached type or matrices and deliver them into one or the other of the tubes according to whether they 115 are reversed or unreversed, the said mechanism including a selecting bridge which controls the point of delivery of the type or matrices.

5. In a typographical machine, the combination of a composed line containing reversed and unreversed type or matrices, means for detaching the type or matrices individually from the line, two distributor tubes, one plain and the other rifled, and au- 125

- omatic mechanism independent of the detaching means to receive the detached type or matrices and deliver them into one or the other of the tubes according to whether they are reversed or unreversed, the said mechanism including a distributor bar along which the type or matrices travel and from which they are released at different points corresponding to the location of the distributor tubes.
6. In a typographical machine, the combination of a composed line containing reversed and unreversed type or matrices, means for detaching the type or matrices individually from the line, two distributor tubes, one plain and the other rifled, and automatic mechanism independent of the detaching means to receive the detached type or matrices and deliver them into one or the other of the tubes according to whether they are reversed or unreversed, the said mechanism including a distributor bar along which the type or matrices travel and formed with two toothed portions separated by an untoothed portion to deliver them at different points according to the location of the tubes, and a selecting bridge arranged beneath the untoothed portion of the bar and serving to permit the disengagement therefrom of the unreversed type or matrices and to effect the reengagement of the reversed type or matrices therewith, for the purpose described.
7. In a typographical machine, the combination of a composed line containing reversed and unreversed type or matrices, each formed with a recess in its bottom edge, means for detaching the type or matrices individually from the line, two distributor tubes, one plain and the other rifled, and automatic mechanism independent of the detaching means to receive the detached type or matrices and deliver them into one or the other of the tubes according to whether they are reversed or unreversed, said mechanism including a distributor bar formed with two toothed portions separated by an untoothed portion, and a selecting bridge arranged beneath the untoothed portion of the bar, said bridge being located in position to enter the recesses of the unreversed type or matrices to permit their disengagement from the bar and arranged to one side of the recesses of the reversed type or matrices so as to effect their reengagement with the bar, all for the purpose described.
8. In a typographical machine comprising reversible type or matrices, the combination of a single distributor, a plurality of tubes leading thereto, and separating mechanism for delivering the type or matrices to one or another of the tubes, the said mechanism comprising devices for releasing the reversed and unreversed type or matrices at different points, and means for insuring the discharge

of the type or matrices into said tubes at different relative intervals, irrespective of their period of delivery to said separating mechanism.

9. In a typographical machine comprising reversible type or matrices, the combination of a single distributor, a plurality of tubes leading thereto, and separating mechanism for delivering the type or matrices to one or another of the tubes, the said mechanism comprising means for releasing the reversed and unreversed type or matrices at different points, and means for carrying the type or matrices different distances from these respective points preparatory to their discharge into the corresponding tubes.

10. In a typographical machine, comprising reversible type or matrices, the combination of a single distributor, a plurality of tubes leading thereto, and separating mechanism for delivering the type or matrices to one or another of the tubes, the said mechanism comprising a distributor bar to release the reversed and unreversed type or matrices at different points, and supporting rails to receive the released type or matrices, the said rails being formed to carry them different distances from the respective points of release preparatory to their discharge into the corresponding tubes.

11. In a typographical machine comprising reversible type or matrices, the combination of a single distributor, a plurality of tubes leading thereto, and separating mechanism comprising means to discharge the reversed and unreversed type or matrices at different points located above the respective tubes, the said points being so arranged as to prevent the discharge of the type or matrices into different tubes at the same time.

12. In a typographical machine comprising reversible type or matrices, the combination of a single distributor, a plurality of tubes leading thereto, and separating mechanism for delivering the type or matrices to one or another of the tubes according to whether they are reversed or unreversed, the said separating mechanism comprising a rotatable screw to propel the type or matrices therethrough, and means for insuring the discharge of the type or matrices into the tubes in different angular positions of the screw during one given complete rotation thereof.

13. In a typographical machine comprising reversible type or matrices, the combination of a single distributor, a plurality of tubes leading thereto, and separating mechanism for delivering the type or matrices to one or another of the tubes, the said separating mechanism comprising a distributor bar to release the reversed and unreversed type or matrices at different points, supporting rails to receive the released type or matrices, and a rotatable screw to propel the

matrices along the distributor bar and rails, the said rails being so proportioned as to discharge the type or matrices into the several tubes in different angular positions of 5 the screw during one given complete rotation thereof.

14. In a typographical machine comprising reversible type or matrices, the combination of a single distributor, a plurality of 10 tubes leading thereto, and separating mechanism for delivering the type or matrices to one or another of the tubes, the said separating mechanism comprising means to discharge the reversed and unreversed type or

matrices at different points, and a rotatable 15 screw to propel the type or matrices through said mechanism, the said points being so selected as to prevent the simultaneous discharge of the type or matrices into different tubes in the same angular position of the 20 screw.

In testimony whereof I have affixed my signature in presence of two witnesses.

DAVID S. KENNEDY.
